SWITCH CONTROL

Arnold Buttner, Brooklyn, N. Y., assignor of one-half to Trump Products Corporation, New York, N. Y., a corporation of New York

Application December 20, 1939, Serial No. 310,104

6 Claims. (Cl. 200—38)

This invention relates to new and useful improvements in switch controls, and it has particularly for its purpose to provide a combined switch control for radio-clocks, television apparatus, and other similar instruments.

With the above and other objects in view, this invention consists of the novel features of construction, combination and arrangement of parts, hereinafter fully described, claimed and illustrated in the accompanying drawings, forming part of this application, and in which similar characters of reference indicate corresponding parts in all views, and in which:

Figure 1 is a side elevational view of my invention.

Figure 2 is a transverse vertical sectional view of my invention, as illustrated in Figure 1, showing the clock mechanism in somewhat enlarged elevation.

Figure 3 is a vertical section, taken on the line 3—3 in Figure 2.

Figure 4 is a vertical section, taken on the line 4—4 in Figure 2.

Figure 5 is a vertical section, taken on the line 5—5 in Figure 2.

Figure 6 is a horizontal section, taken on the line 6—6 in Figure 2.

Figure 7 is a horizontal section, taken on the line 7—7 in Figure 2.

Figure 8 is a vertical section, taken on the line 8—8 in Figure 2; while

Figure 9 is a transverse vertical section, similar to Figure 2, but of a modified form, with parts of the clock mechanism shown in elevation.

Figure 10 is a vertical section, taken on the line 10—10 in Figure 9; and

Figure 11 is a vertical section, taken on the line 11—11 in Figure 9.

Referring particularly to the drawings, and more especially to the views from 1 to 8, inclusive, 15 indicates the housing of an electric clock, having the usual dial 16 and the motor 17; the minute hand 18 is attached to a shaft 19, which carries a gear 20, cooperating with the latter is a gear 21, and a train of gears 22, relatively mounted with respect to each other, so as to engage the pinion 23 of a rotor shaft 24, which in turn causes the rotation of the shaft 19.

The hour hand 25 is secured to a sleeve 26, which carries a gear 27 meshing with a pinion 28, which, in turn, by cooperation of the gears 20, 21 and the train of gears 22 with the pinion 23, mounted upon the rotor shaft 24, causes the hour hand to rotate.

55 The aforesaid gear arrangements, relative to

the operation of the minute and hour hands, with their relevant shafts, are, however, merely of the conventional construction.

A time indicating hand 29, forming part of a circuit closing mechanism, is rotatably mounted on a sleeve 30, to one side of a plate 31; the latter has also secured thereto the dial plate 16 by means of bushings 32. To said sleeve 30 is fixedly connected a gear 33 by means of set screws 34. The said gear 33 is engaged by a worm 35 secured to the shaft 36, which is mounted in bearings 37 attached to the plate 31, as may be seen in the Figures 2 and 3.

The end of the shaft 36, which protrudes from the housing 15, is provided with a knob 38 by which the time indicating hand 29 may be regulated or set to a predetermined time for the starting of a radio.

A contact spring 39 carries a pin 40, which passes through an aperture 41 and engages an outer contact ring 42 secured to a disk 43, while a second contact spring 44, which carries a pin 45, passes through the aperture 46 and engages an inner contact ring 47, which is also mounted on the disk 43; said disk 43 is secured to the sleeve 30 on the opposite side of the plate 31.

A spring 48 is interposed between the plate 31 and the gear 33 to insure proper contact between the pins 40 and 45 and the contact rings 42 and 47.

The outer contact ring 42 has secured thereto a bracket or arm 49, which carries a contact spring 50, and has a pin 51 fixedly secured thereto. To the inner contact ring 47 is secured a bracket 52, which is adapted to be engaged at a predetermined time by the contact spring 50, to close the circuit, as will be hereinafter more fully described.

A disk 53 is slidably mounted on the shaft 26 by means of the slot 54 and the set screw 55; said disk 53 carries a triangular raised portion 56, secured to the latter by screws or pins 57.

When the disk 53 is rotated, this triangular raised portion, or projection 56 engages the pin 51 of the contact spring 50 pressing the latter down against the bracket 52, and thereby closes the circuit referred to above.

The disk 53 extends into an angular groove 58, which is engaged by an eccentric 59 carried by the shaft 60 and supported by brackets 61 secured to a plate 62, which latter by means of sleeves 62a is secured to the plate 31.

The eccentric 59 permits the horizontal adjustment of the disk 53, whereby to provide an engagement of a shorter or longer duration between the pin 51 and the raised triangular projection 56,

incidentally closing the circuit for a shorter or longer period of time, as may be desired.

Thus, for illustration it may be stated that, if the disk 53 is in a position where the dotted and dash line 63 would be in alignment with the pin 51, the duration for the closing of the circuit would be one-quarter of an hour, whereas, if the dotted and dash line 64 would be in alignment with the pin 51, the circuit would be closed for the duration of an hour.

To regulate and clearly indicate these adjustable means, a knob 65 is secured at the end of the shaft 60, this latter knob also carries a pointer 66 adapted to travel over the indicating scale 67 on the top of the housing 15. Wires 68 and 69 leading to a source of current (not shown) are connected to the motor 17 to energize the latter for the operation of the clock mechanism. The wire 68 is also connected by a wire 70 to the contact spring 44, thereby providing a current for the inner contact ring 47, which, when the contacts 50 and 52 are closed by means of the disk 53 and projection 56, allows the current to pass from the inner ring 47 to the outer ring 42, and by means 25 of the contact spring 39 and a wire 71 to one terminal of an outlet 73; the other terminal of said outlet 73 is connected by a wire 74 to the wire 69.

A radio, when connected by the wire 75 and plug 30 76 to the outlet 73, will thereby be energized upon closing the circuit.

The wire 70 is connected by a wire 77 to one side of a switch 78 mounted through the top of the housing 15, while the other side of said switch 35 is connected by a wire 79 to the wire 71. By closing the switch 78 the current will flow through wires 68 and 77 through the switch 78 and through wires 79 and 71 to one terminal of the outlet 73; the outer or other terminal of the outlet 40 having been connected, as before mentioned by the wire 74 to the source of current.

Thus it will be clearly seen that by closing the switch 78, the current will be closed indefinitely, until a reopening of said switch. During 45 this stage the time switch hereinbefore mentioned will naturally be ineffective in operation.

Referring to the modification shown in the Figures 9, 10 and 11, similar numerals will be used, as before, in said views, but with a prime 50 added thereto.

To the end of the sleeve 36' is secured the disk 43', which, as similarly described before, is provided with an outer contact ring 42' and an inner contact ring 47', these rings are electrically connected by contact springs 39' and 44'. To the outer ring 42' is secured a contact spring 80 provided with a pin 81. Another contact spring 82 is connected to the inner ring 47', and has fixed thereon a contact point 83. A bushing 84 is 60 mounted on sleeve 26', said bushing is provided with angular flanges 85 to form a retaining means for an arm 86, said arm is adjustable by means of the slot 87 and adjusting screw 88, the lower end of which projects into the sleeve 26' for the 65 purpose of insuring the simultaneous rotation of the bushing 84 and sleeve 26'.

A spring 90 makes the adjusting screw 88 contact the sleeve 26'. The longer end of the arm 88 is provided with a bevelled surface, which by 70 means of the adjusting screw 88 offers an extended surface to be contacted by the pin 81 of the spring 80, which, thus, in turn, determines the relative length of time the circuit is closed.

In order to facilitate the operation of the adjusting screw 88 from the outside of the housing 75

15', a rod 91 guided in a bracket 92 is at its lower end narrowed for engagement with a slot of the adjacent screw 88, the other end of the rod 91 carries a knob 93 for actuating the latter. A spring 94 is interposed between the knob 93 and the housing 15' to disengage the rod 91 from the adjusting screw 88 after the operative adjustment has been made; the rod 91 then comes to rest against the stop 95.

It is obvious that changes may be made in the form, construction and arrangement of the several parts, as shown, within the appended claims, without departing from the spirit of the invention, and I do not, therefore, wish to limit myself to the exact construction and arrangement shown and described herein.

What I claim, as new and desire to secure by Letters Patent of the United States, is:

1. In a time switch of the character described, comprising in combination a gear train, an indicating hand mounted on a sleeve of the hour shaft of said gear train, a worm gear mounted on said sleeve, a worm rotatable by an outside knob mounted adjacent to said worm gear, an insulating disk fastened to the rear of said sleeve, a plurality of slip rings mounted on said insulating disk, a plurality of sliding contacts in engagement with said slip rings, a normally open spring type switch connecting said slip rings and rotatable with said insulating disk, said sleeve and said indicating hand by turning said worm, a cam mounted on the hour shaft of said gear train and fastened to said shaft, said cam being in engagement with said spring type switch once for every revolution of the hour shaft. 20

2. In a time switch of the character described, 25

comprising in combination a gear train, an indicating hand mounted on a sleeve of the hour shaft of said gear train, a worm gear mounted on said sleeve, a worm rotatable by an outside 30

knob mounted adjacent to said worm gear, an insulating disk fastened to the rear of said sleeve; 35

a plurality of slip rings mounted on said insulating disk, a plurality of sliding contacts in en- 40

gagement with said slip rings, a normally open 45

spring type switch connecting said slip rings and rotatable with said insulating disk, said sleeve 50

and said indicating hand by turning said worm, 55

a cam mounted on the hour shaft of said gear train and fastened to said shaft, said cam being in engagement with said spring type switch once

for every revolution of the hour shaft, a normally 60

open push button switch connected across said 65

spring type switch, whereby said spring type 70

switch may be shunted for any length of time 75

ranging from zero to one hour.

3. In a time switch of the character described, 80

comprising in combination a gear train, an indicating hand mounted on a sleeve of the hour

shaft of said gear train, a worm gear mounted 85

on said sleeve, a worm rotatable by an outside

knob mounted adjacent to said worm gear, an 90

insulating disk fastened to the rear of said sleeve;

a plurality of slip rings mounted on said insulat- 95

ing disk, a plurality of sliding contacts in en- 100

gagement with said slip rings, a normally open 105

spring type switch connecting said slip rings and 110

rotatable with said insulating disk, said sleeve 115

and said indicating hand by turning said worm, 120

a cam mounted on the hour shaft of said gear train and rotatable by said hour shaft and being 125

slidable axially on said shaft, said cam having 130

on one side an annular groove, an eccentric ro- 135

tatably mounted in engagement with said annu- 140

lar groove, a triangular projection located on the 145

150

- outer periphery of said cam, whereby through the adjustment of said eccentric, said cam may engage said normally open spring type switch for various lengths of time.
5. 4. In a time switch of the character described, comprising in combination a gear train, an indicating hand mounted on a sleeve of the hour shaft of said gear train, a worm gear mounted on said sleeve, a worm rotatable by an outside 10 knob mounted adjacent to said worm gear, an insulating disk fastened to the rear of said sleeve, a plurality of slip rings mounted on said insulating disk, a plurality of sliding contacts in engagement with said slip rings, a normally open 15 spring type switch connecting said slip rings and rotatable with said insulating disk, said sleeve and said indicating hand by turning said worm, a cam mounted on the hour shaft of said gear train and rotatable by said hour shaft and being 20 slidable axially on said shaft, said cam having on one side an annular groove, an eccentric rotatably mounted in engagement with said annular groove, a triangular projection located on the outer periphery of said cam, whereby through 25 the adjustment of said eccentric, said cam may engage said normally open spring type switch for

various lengths of time, and plug receptacles connected to said slide contacts, whereby a radio set may be connected and operated by said switch.

5. A time switch comprising a sleeve having a hand, a gear and a disk mounted thereon, said disk carrying contact rings, a cam slidably mounted on a shaft and being provided with a triangular raised portion, a switch member adapted to bridge the contact rings when engaging said triangular portion, whereby to complete the connection between one wire of an electrical source and one outlet-terminal, the other outlet terminal being connected to the other wire of the electrical source.

6. A time switch comprising a sleeve having a hand, a gear and a disk mounted thereon, contact rings carried by said disk, a cam formed with a slanting surface and guided within a bushing, a spring and a set screw in cooperation for the adjustment of said slanting surface, a rod provided 20 with a knob at one end thereof, the other end of said rod being adapted to contact the set screw, said cam being made to actuate a contact switch, whereby to bridge the contact rings of the disk, substantially as and for the purpose set forth. 25

ARNOLD BUTTNER.
